UNITED STATES PATENT OFFICE.

FRED F. DOW, OF FREDERICTON, CANADA.

BURNER.

SPECIFICATION forming part of Letters Patent No. 738,779, dated September 15, 1903.

Application filed January 20, 1902. Serial No. 90,406. (No model.)

To all whom it may concern:

Be it known that I, FRED F. DOW, a citizen of the United States, residing at Fredericton, in the county of York, Province of New Brunswick, Canada, have invented a certain new and useful Improvement in Burners, of which the following is a specification, reference being had therein to the accompanying drawings.

10 My invention has for its object to provide an economical and powerful hydrocarbon burner or heater especially fitted for use upon steam-propelled vehicles, as also in other connections requiring an efficient and compact device of this kind.

15 The invention will be fully understood from the following description, taken in connection with the accompanying drawings, and in the claims at the close of the specification the novel features thereof are pointed out and clearly defined.

20 In the drawings, Figure 1 is a plan view of a burner containing one embodiment of my invention. Fig. 2 shows the said burner in transverse vertical section on the plane indicated by dotted line 2 2 in Fig. 1. Fig. 3 is a side elevation showing the starting-coil, the case or holder for the latter being partially broken away to more fully show the arrangement of the said coil. Fig. 4 is a vertical sectional view of the starting-coil holder. Fig. 5 shows detached the starting-coil and its connections, and the connections by means of which gas is supplied to the mixing-tubes.

25 35 The main shell of a burner or heater embodying my invention is represented at *a*, Figs. 1 and 2. The top and bottom sheets of the burner or heater are designated *b* and *c*, respectively. When employed upon a steam-

40 45 propelled motor-vehicle in connection with the steam-generator of the latter, the heater or burner usually is surrounded by an inclosing cylindrical shell or casing *d*, Figs. 1, 2, and 3, which, however, in itself constitutes no part of my invention, although combined in certain relations with certain features thereof in some cases. The space inclosed by the shell *a* and the top and bottom sheets *b* *c* constitutes the main gas-chamber *x*, with-

50 55 in which is received the fuel-supply in the form of vapor or gas commingled with air. The top sheet *b* is provided with burner-out-

lets *e*, Figs. 1 and 2, which are preferably formed in groups, each group comprising a considerable number of openings or perforations formed in a circular plate *f*. The plates *f* are screwed or otherwise suitably secured in circular openings formed to receive them in the top sheet *b*. This particular construction is a convenient form; but, as will be obvious, other forms of construction may be employed the essential feature being openings or outlets connecting the gas-chamber with the space above the top sheet, through which outlets gas may issue and be burned above the top sheet. To the proper burning of the gas above the top sheet a suitable supply of air is necessary. For the purpose of supplying this air I provide intermediate the plates *f* air tubes or flues *w*, which project across the interior space of the burner and enter the top and bottom sheets. Through these tubes air may pass freely from a point below the burner to a point above the top sheet, where the combustion of the gas is proceeding.

60 65 70 75 Centrally disposed with relation to the main gas-chamber I provide an auxiliary gas-chamber *y*, as shown. The shell *i* of such chamber (see Fig. 2) is for convenience of construction attached to the top sheet of the burner, preferably on the under side thereof, so that the auxiliary gas-chamber is contained within the main gas-chamber, as shown. By this construction the auxiliary gas-chamber does not operate in any way to increase the height of the burner, which is desirable.

80 85 90 95 As above stated and as shown in the embodiment of my invention illustrated in the accompanying drawings, the auxiliary gas-chamber is located centrally of the main gas-chamber. The precise location is obviously wholly immaterial so long as it is such that the vaporizer, hereinafter described, may be suitably placed and arranged in relation thereto, and it will be clear that more than one auxiliary chamber might be employed, especially in heaters of large size, in which it might be desirable to employ more than one vaporizer.

100 The flat top of the auxiliary gas-chamber is furnished with burner-outlets constituted by small holes or perforations *e*, extending through the same. The said burner-outlets

are preferably quite numerous and located quite closely to each other, forming, in effect, a large group or a number of individual groups, intermediate which are tubes w^5 , extending downwardly through the bottom sheet, which are provided for the passage of a supply of air.

The respective gas-chambers of a burner or heater embodying my invention are provided 10 with mixing-pipes through which the required volumes of vapor or gas commingled with air are caused to flow into the said gas-chambers, each mixing-pipe having in connection therewith a jet-valve or needle-valve, by means of 15 which the required flow may be controlled as necessary. In Figs. 1 and 2 the mixing-pipe delivering into the auxiliary gas-chamber is designated k , and two mixing-pipes $m m'$ are shown arranged to deliver into the main gas- 20 chamber x . The corresponding jet-valves or needle-valves delivering vapor or gas into the open outer ends of the said mixing-pipes are designated n in the case of that pertaining to mixing-pipe k for the auxiliary gas-chamber 25 y , and $o o'$ in the case of those pertaining to the mixing-pipes $m m'$ of the main gas-chamber x in said figures. The number of mixing-pipes, &c., employed in connection with the respective gas-chambers may be varied 30 as may be necessary. Usually one will suffice for the auxiliary gas-chamber and one or more may be used with the main gas-chamber.

At the top of the burner I arrange above the burner-outlets of both the outer series e 35 and the central series e^2 a vapor generator or vaporizer p , Figs. 1 and 2. The vaporizer shown in the accompanying drawings was designed especially for kerosene or the heavier hydrocarbons. It is in communication with 40 a suitable source of fuel-supply, which will be usually a container. (Not necessary to be shown.) It also is in communication with the jet-valves or needle-valves, from which last the fuel passes in the forms of jets of vapor 45 or gas into the open outer ends of the mixing-pipes. The vaporizer p is represented in the drawings as of tubular form, circular in cross-section, although it obviously may be of any preferred shape in cross-section. Its interior 50 passage is of relatively great length in proportion to its cross-sectional capacity and is preferably in that respect uniform throughout. It is preferred that the cross-sectional capacity should be relatively small in order 55 that the greatest possible efficiency of the degree of heat which is applied may be secured by exposing the contents of said vaporizer to the full effect of such heat and that by subjecting all portions of such contents alike to 60 such effect they may be uniformly acted upon and converted thereby. Preferably I arrange and combine the vaporizer and the burner-outlets so as to cause the contents of the former to be subjected to the action of heat of increased intensities. In the embodiment of 65 my invention illustrated in the accompanying drawings one portion, as D , of the vapo-

rizer is placed above the burner-outlets e of the main gas-chamber. Herein this portion D extends radially inward from the periphery of the burner toward the center of the top of the burner. The disposition thereof in this particular relation is not essential, however, so long as the coil C of the vaporizer p is so located as to receive the effect of the 75 heat from the burner-outlets e^2 of the auxiliary chamber. When the burner is in full operation, the said radially-extending portion D is subjected to the heat of the flames produced by the combustion of the streams of 80 vapor or gas commingled with air which rise from said burner-outlets e in proximity thereto. The greatest intensity of heat, however, is not applied to this portion. This portion of the vaporizer is that through which the 85 supply of liquid fuel first flows and from which it passes to the more intensely-heated coil C , located above the auxiliary chamber. The coil C and the auxiliary chamber are preferably located at the center of the burner, especially in burners of relatively small size. The said coil C and the burner-outlets e^2 are arranged and combined to cause the contents of the vaporizer to be subjected to a very high 90 temperature. Succeeding portions or turns 95 of the coil are preferably slightly raised in height, as shown, whereby increased intensities of heat are applied to the contents of the vaporizer.

From the coil the vaporizer extends outward to the periphery of the burners, where it communicates with the jet-valves n , o , and o' . After passing the coil C the contents of the vaporizer in the condition of a vapor or gas of high tension flow outward through the 100 discharge portion B of the vaporizer to the distributing-chamber q and thence to the jet-valves and discharge therefrom through suitable connections into the mixing-pipes, passing through the latter into the respective chambers x and y . The relatively great length in proportion to the diameter or cross-sectional capacity which is characteristic of my vaporizing device insures that substantially all portions of the contents of the vaporizer shall be subjected alike to the effect 105 of the heat, and thus that they shall be uniformly converted under the protracted and intense action of the heat which is applied. In actual practice I have found that a vaporizing-tube of substantially three-eighths of an inch in interior diameter and forty inches in length from the point at which it first receives the direct action of the heat of the burner to the point at which it is united with 110 the connections for the jet-valves (these measurements including the discharge portion B) gives very satisfactory results; but I do not confine myself to these proportions. 115

The outer extremity of the vaporizer is 120 connected with a chambered body or short section of pipe, the same being designated q , Figs. 2 and 5. For convenience in reference I have termed this section a "distributing-

chamber," since it is furnished with connecting pipes or extensions which lead to the respective jet-valves or needle-valves and convey supplies of vapor or gas to the latter.

5 Its precise form and character and the mode and form of its connection with the vaporizer and the jet-valves or needle-valves are not material. As shown, (see Fig. 5,) the interior space of the chambered body *q* is connected with the various valves *n o o'* by means of separate short lengths of pipe *n³ n⁴ n⁵*, respectively.

One special feature of the invention is the convenient provision made for starting the 15 heater or burner. Thus I combine with the vaporizer and the jet-valve *n* a supplemental length of pipe, preferably in the form of a coil, within which a portion of the kerosene or heavy hydrocarbon that is contained in 20 the vaporizer at the time of starting may conveniently be converted into vapor by the ready application of heat whereby to produce a supply of vapor which is sufficient to fill the auxiliary gas-chamber *y*, occasioning a 25 flow of vapor through the central burner-outlets, which may be lighted so as to heat the central coil of the vaporizer.

The starting-coil is designated *r*. It does not form a part of the main pipe system 30 through which the circulation of the fluid fuel is maintained during the normal operation of the burner; but it is supplemental thereto and is used only when the burner is to be started, after which it is preferably cut 35 out and shut off from the main system. To this end it is connected at its inlet end to a suitable source of liquid-fuel supply and at its opposite or discharge end to an instrumentality through which the auxiliary chamber *y* is supplied with the vapor or gas generated in it. For this purpose I find it convenient to connect its inlet with the outgoing portion *B* of the main vaporizer *C*, as at *r'*, Figs. 1 and 5, and its outlet with the jet-valve *n* of the mixing-pipe *k*, through which the auxiliary chamber *y* is supplied, as at *r²*, Figs. 1, 3, and 5. The distributing-chamber *q*, which in the main circulation system is located between the two points of connection 40 *r' r²* of the starting-coil, is formed with a valve-seat *r³*, with which the inner end of the valve-stem *r⁴* co-operates and by means of which communication between the main vaporizer *C* and the several jet-valves is controlled. 45 At some point between its inlet *r'* and its outlet *r²* the starting-coil is provided with a valve *r⁵*, Fig. 5, by means of which communication between the source of fuel-supply (in this instance *B*) and the starting-coil *r* can be made or closed as desired. As shown, the valve is represented as located about midway on the coil; but manifestly it can be located differently, if desired. I prefer to place it near to the outlet *r²*, so as to 55 prevent the gas-jet of the needle-valve *n* when established from sucking or drawing out along with it the liquid contents, if any

there be, of the coil *r*. In starting the burner if the valve *r⁵* be opened (the valve *r⁴* being closed) the oil under pressure from pipe *B* will pass into the starting-coil, and if heat be applied to the latter the oil will be vaporized and the vapor will pass through the outlet *r²* to the jet-valve *n* of the mixing-pipe *k*, thus supplying to the central chamber *y* the 75 gaseous fuel requisite to heat the main vaporizer *C*.

If desired, the starting-coil may be arranged to be heated by means of a torch suitably applied and held when it is desired to 80 start the burner or heater; but preferably I provide a case or housing *s*, Fig. 3, within which the coil is suspended, as by hooks *s⁵*, or otherwise suitably secured, and the lower portion of which serves to hold a suitable 85 quantity of inflammable substance, which may be lighted and which will serve to properly heat the coil. In practice I prefer to place in the lower portion of the case or housing *s* a quantity of asbestos or other suitable 90 absorbent material, which I saturate with alcohol or the like for the purpose of heating the starting-coil. At the lower front portion or outside of the housing *s* I provide a series of draft-holes *s²*. These small holes not only 95 supply air to the burning alcohol or other material which is employed to heat the starting-coil, but they also serve as convenient openings through which the alcohol may be placed in the absorbent material within the 100 lower portion of the case or housing and there ignited. For convenience I have hinged the outer wall of the case *s*, as at *s⁷*, and at the opposite side of the wall or door have provided a securing device *s⁸*. The case or housing 105 is preferably of the shape shown and suitably secured to the casing of the burner. By forming it as shown it does not project far from the burner-case, is neat and compact, and occupies only a minimum of space. 110 The precise arrangement and disposition of the coil is not material. The interior of the housing may be lined with asbestos or other suitable non-heat-conducting material. The convolutions of the starting-coil are preferably 115 separated as well as in a degree supported by interlacing wires *s⁶* or the like. When the burner is not in use, by closing the valves *r⁵* and *r⁴* the flow of vapor or gas to the jet-valves or needle-valves is entirely prevented. 120

In operation the heater or burner will be started by closing the valves pertaining to the mixing-pipes *m m'* of the main gas-chamber *x*, closing also the valve *n*, pertaining to the mixing-pipe *k* of the auxiliary gas-chamber *y*, closing the valve *r⁴*, and opening valve *r⁵* of the starting-coil. Then on heating the starting-coil by the ignition of alcohol in the case or housing *s* the liquid kerosene which passes into the same from the vaporizer *p* 125 will become vaporized, after which by opening valve *n* the said vapor or gas may be caused to flow through the mixing-pipe *k* into the auxiliary gas-chamber *y*. As soon as 130

streams of vapor or gas commingled with air begin to issue from the central or auxiliary burner-outlets e^2 these streams will be ignited, and the resulting flames will heat the central coil C of the vaporizer. After vapor forms sufficiently within the vaporizer the valve r^5 of the starting-coil will be closed, then cutting out the starting-coil from the main circulation system, and the valve r^4 will be opened. When all is in readiness for starting the main burner, the valves o o' will be opened, causing vapor to flow through the corresponding mixing-pipes m m' into the main gas-chamber x . As soon as streams of commingled vapor or gas and air begin to issue from the main burner-outlets e such streams are ignited from the flames of the central burner-outlets e^2 . When the use of the heater or burner is to be discontinued temporarily, the valves o o' will be closed, leaving valve n open. This will discontinue the flow into the main chamber x ; but the flow into the auxiliary gas-chamber y will continue, so that the flames from the burner-outlets e^2 in connection with the said auxiliary gas-chamber will continue burning and will maintain a constant supply of vapor or gas of high tension within the vaporizer. The said flames also serve to relight the streams of vapor or gas which will issue from the main burner-outlets e when the valves o o' are opened again.

By the employment of my invention a compact and efficient burner especially adapted for the use of the heavier hydrocarbons as a fuel may be constructed. The device is very quickly put into full operation by the employment of the starting-coil, which latter is connected and disconnected with the fuel-supply at will and plays no part in the operation of the burner after it has performed its function of first starting the burner in operation. When the device is in operation, the main burners are readily controlled. When temporarily out of use, the main burners may be cut off, obviating waste and effecting economy in fuel without interfering with the maintenance of a supply of gas necessary to instantly start them again and continue them in operation. When gas is supplied to the main burners, it instantly ignites from the burners connected with the auxiliary chamber, the gas arising from which latter is kept constantly burning in such volume and in such relation to the coil as to heat the vaporizer effectively and reduce to a minimum the danger of the flame being extinguished by an unusual draft. By reason of these advantages my invention, as will be clear, is particularly adapted for use in self-propelled vehicles and the like.

What I claim is—

1. A hydrocarbon heater or burner comprising main and auxiliary gas-chambers having burner-outlets, a vaporizer above said burner-outlets to receive heat therefrom, connections from such vaporizer arranged to discharge vapor into the main and auxiliary gas-cham-

bers a coil auxiliary vaporizer arranged to discharge into said auxiliary gas-chamber, and means independent of said burner-outlets arranged to heat said auxiliary vaporizer, substantially as described. 70

2. A hydrocarbon heater or burner comprising main and auxiliary gas-chambers having burner-outlets, a vaporizer above said burner-outlets to receive heat therefrom, connections from such vaporizer arranged to discharge vapor into the main and auxiliary gas-chambers, a coil auxiliary vaporizer arranged to discharge into said connections, and means independent of said burner-outlets arranged to heat said auxiliary vaporizer, substantially as described. 75

3. A hydrocarbon heater or burner comprising main and auxiliary gas-chambers having burner-outlets, a vaporizer receiving heat from said burner-outlets, connections from such vaporizer arranged to discharge vapor into the main and auxiliary gas-chambers, a coil auxiliary vaporizer arranged to discharge into said auxiliary gas-chamber, means for controlling the flow through said auxiliary vaporizer, and means independent of said burner-outlets arranged to heat said auxiliary vaporizer, substantially as described. 80

4. A hydrocarbon heater or burner comprising a gas-chamber having burner-outlets, a vaporizer receiving fuel at one end and from the other end of which vapor passes to said gas-chamber, said vaporizer being heated from said burner-outlets, a vapor-supply conduit intermediate said vaporizer and said gas-chamber, a starting-coil connected at one end with a source of oil-supply and connected at the other end with the said vapor-supply conduit, and means independent of the burner-outlets to heat the said coil, substantially as described. 85

5. A hydrocarbon heater or burner comprising a gas-chamber having burner-outlets, a main circulation system, a main vaporizer forming a part of said system, supplied with oil therethrough, and receiving heat directly from said burner-outlets, a conduit also forming part of said system and conveying the vapor from said vaporizer to the gas-chamber, an auxiliary or starting coil connected with the said system, receiving oil therethrough, and supplying vapor to the said conduit, and means independent of the burner-outlets to heat the said coil, substantially as described. 90

6. A hydrocarbon heater or burner comprising a gas-chamber provided with burner-outlets; a vaporizer receiving heat from said burner-outlets and supplying vapor or gas to said gas-chamber; means to control the flow of vapor or gas to the said burner-outlets; a starting-coil connected with said vaporizer and supplying vapor or gas to said burner-outlets, and means to permit flow from the vaporizer through said starting-coil and disestablish direct communication between the vaporizer and the burner-outlets in starting up, and to prevent flow from the vaporizer 95

through said starting-coil and establish direct communication between the vaporizer and the burner-outlets during the regular working of the heater or burner, substantially as described.

7. A hydrocarbon burner or heater comprising main and auxiliary gas-chambers provided with burner-outlets; a vaporizer receiving heat from said outlets and supplying vapor or gas to said chambers; means to control the flow to the respective series of burner-outlets; a starting-coil connected with said vaporizer and also adapted to supply vapor or gas to said burner-outlets; and means to permit flow from said vaporizer through said starting-coil and disestablish direct communication between the vaporizer and the burner-outlets in starting up, and to prevent flow from the vaporizer through said starting-coil and establish direct communication between the vaporizer and the burner-outlets during the regular working of the heater or burner, substantially as described.

8. A hydrocarbon heater or burner comprising main and auxiliary gas-chambers provided with burner-outlets; a vaporizer receiving heat from said outlets and supplying vapor or gas thereto; means to control the flow to the respective series of burner-outlets; a starting-coil connected with said vaporizer and also adapted to supply vapor or gas to the burner-outlets of said auxiliary gas-chamber, and a valve to permit flow from the vaporizer through said starting-coil and disestablish direct communication between the vaporizer and the burner-outlets in starting up, and to prevent flow from the vaporizer through said starting-coil and establish direct communication between the vaporizer and the burner-outlets during the regular working of the heater or burner substantially as described.

9. The improved hydrocarbon-burner comprising a main gas-chamber provided with burner-outlets; an auxiliary gas-chamber

provided with burner-outlets; mixing-pipes respectively supplying the respective gas-chambers; a vaporizer so placed as to receive heat from both series of said burner-outlets; valves respectively discharging the vapor generated by said vaporizer into said respective mixing-pipes; a starting-coil connected with said vaporizer; and means to permit flow from the vaporizer through said starting-coil and disestablish direct communication between the vaporizer and said valves, in starting up, and to prevent flow from the vaporizer through said starting-coil and establish direct communication between the vaporizer and the burner-outlets during the regular working of the heater or burner, substantially as described.

10. The improved hydrocarbon-burner comprising a main gas-chamber provided with burner-outlets; an auxiliary gas-chamber provided with burner-outlets; mixing-pipes respectively supplying the respective gas-chambers; a vaporizer in position to receive heat from both series of burner-outlets; a distributing-chamber in communication with said vaporizer; valves respectively receiving vapor from said distributing-chamber and discharging the same into the respective mixing-pipes; a starting-coil in communication with the said vaporizer; and means to disestablish flow from the vaporizer to the said distributing-chamber and permit flow therefrom through the starting-coil, in starting up, and to prevent flow from the vaporizer through said starting-coil and establish direct communication between the vaporizer and the burner-outlets during the regular working of the heater or burner, substantially as described.

In testimony whereof I affix my signature in presence of two witnesses.

FRED F. DOW.
